UNITED STATES PATENT OFFICE.

WILLIAM T. MURPHY, OF BROOKLYN, NEW YORK.

DESIGN FOR BORDER AND BACKGROUND FOR PICTURES.

Specification forming part of Design No. 7,943, dated December 22, 1874; application filed October 31, 1874.
[Term of Patent 3½ years.]

To all whom it may concern:

Be it known that I, WILLIAM T. MURPHY, of Brooklyn, Kings county, New York, have invented a Design for Relief-Border for Pictures, of which the following is a specification:

My invention relates to a design for ornamental relief-border and backing for pictures of all kinds, the nature of which is fully shown in the accompanying photographic illustration of the same, to which reference is made.

A represents a photograph or other picture, which is placed on a mineral background, B, of suitable color, inclosed by a round or oval inner band, border, or frame, C, that is painted in gold, silver, or other color on the rear side of the picture-covering glass. The outer shape of border C is square or oblong, with a spurred and pointed band, D, running along the outside of the same, the part between the inner oval and the outer band being filled up with suitable ornamental scrolls of gold or other color, brought out by a backing of correspond-

ing and appropriate colors. Heart or leaf shaped parts D' extend at the corners in diagonal, and midwise between the corners in rectangular, direction from the outer band, being also scrolled and backed in suitable manner.

The design serves to bring out the picture in fine relief, forming an elegant and highly-ornamental border and relief-backing for the same.

I claim as my invention—

The design for ornamental border and background for pictures, composed of the spurred band D, sight-band C, intermediate scroll-work E, heart-shaped corner and side pieces D', and granulated background B, substantially as described, and shown in the accompanying photographic illustration.

WM. T. MURPHY.
